CARTRIDGE FOR TOY GUNS

Original Filed Sept. 30, 1926

UNITED STATES PATENT OFFICE

FREDERICK HENKE, OF PHILADELPHIA, PENNSYLVANIA, ASSIGNOR, BY MESNE ASSIGNMENTS, TO A. H. FOX GUN COMPANY, OF PHILADELPHIA, PENNSYLVANIA, A CORPORATION OF PENNSYLVANIA

CARTRIDGE FOR TOY GUNS

Application filed September 30, 1926, Serial No. 138,606. Renewed April 9, 1929.

The present invention relates to cartridges for toy guns and more particularly to cartridges in which no explosive is employed, the projectile or ball being discharged from 5 the cartridge cylinder or casing by the impact of a spring impelled plunger mounted within the cartridge casing.

One of the objects of my invention is to provide a cartridge which closely resembles, 10 in outer appearance, the cartridge used in a real fire arm, and which is adapted to be inserted into the breech of a toy shot gun, the same as cartridges are manipulated in loading and unloading real shot guns.

15 A further object of my invention is to provide a toy cartridge in which the impelling force for the projectile is the impact of a plunger with the rear side of the projectile under the impelling force of a compression spring under tension, and to prevent the formation in the casing of air pressure to exert a projecting action on the ball.

20 A further object of my invention is to provide a toy cartridge consisting of relatively few parts, of simple construction, certain in action, and not liable to become inoperative after long use, and which may be manufactured at a reasonable cost.

25 The other objects of my invention will appear in the specification and claims below.

In the drawing forming a part of this specification, and in which the same reference characters are employed throughout the various views to designate the same parts,

30 Fig. 1 is a longitudinal sectional view through the axis of my improved cartridge, the projectile being shown in elevation, in the end of the shell.

Fig. 2 is a section on the line 2—2 of Fig. 1.

35 Fig. 3 is a fragmentary partially sectioned view of the rear end of the cartridge showing in plan view the cartridge head and the latches pivotally mounted therein.

40 Fig. 4 is a longitudinal sectional view, similar to Fig. 1, showing a modified construction.

Fig. 5 is a sectional view on the line 5—5 of Fig. 4.

45 Fig. 6 is a fragmentary sectional view,

similar to Fig. 3, of the modification shown in Fig. 4.

Fig. 7 is a longitudinal sectional view of another modification.

Fig. 8 is a section on line 8—8 of Fig. 7. 55

Fig. 9 is a fragmentary plan view of the cartridge head shown in Fig. 7.

The cartridge forming the subject-matter of this invention consists of a metallic tube, cylinder or casing 1 of substantially uniform 60 diameter outside and inside except that at the discharge end 2 thereof it is substantially reduced in diameter to provide a clean annular shoulder 3 and a forwardly upwardly tapering tip 4. The largest diameter of the tapering bore of the tip 4 is at the end of the casing where it is substantially the same or slightly greater than the diameter of the spherical projectile or ball 5. When a spherical projectile is inserted into the end of the tip 4 and 65 pressed therein it will be retained in the tip quite firmly by the friction between it and the slightly tapering walls of the bore of the tip 4. It may here be stated that the ball 5 is preferably composed of a light soft wood 70 and, since it has no sharp projection on the surface thereof, and since it is light in weight, it may be projected quite rapidly without danger of seriously injuring one who might be hit by the projectile in its flight from a gun. 75

In making the parts of the cartridge, the groove 6 is not formed in the cylindrical wall of the casing until the parts are being assembled, and therefore, for the present, the cartridge casing will be considered as being of 80 uniform outside diameter and bore, except as to the tip 4.

The cartridge head 7 is, generally speaking, a hollow cylindrical member, having a circular flange 8 on one end thereof a little larger 85 in diameter than the outside diameter of the tube or casing 1. The cylindrical bore 9 of the cartridge head 7 is of uniform diameter from the forward end thereof reaching to a point near the flange 8 where a square shoulder 10 90 is provided, and from said shoulder 10 through the rear end and flange thereof, a smaller cylindrical hole 11, co-axial with the head 7, and bore 9 is provided.

The forward cylindrical end of the car- 100

tridge head 7 is provided with two diametrically oppositely disposed longitudinal extending slots 12-12, which are disposed parallel to the axis of the cartridge head 7 extending transversely through the axis of said cartridge head 7, and at right angles to a plane passing through the slots 12, and near the forward end of said head, is a cylindrical pin 13. The outer cylinder surface of the cartridge head 7 is provided with a circumferential groove 14 placed somewhat forwardly from the flange 8. On the pin 13 are pivotally mounted two latches 15-15, side by side and preferably alike in size and form, said latches, however, being reversely mounted on said pin 13. Each latch 15 has a forwardly extending arm 16 provided near the free end thereof with a tooth or detent 17, and the extreme free end or tip 18 of said arm is tapering and terminates in a sharp edge. Each latch 15 is also provided with a somewhat shorter arm 19 normally curving outwardly toward the wall of the cartridge casing and terminates in an outwardly curved arcuate surface 20 normally positioned close to the wall of the bore 9 in the head 7. The latches 15 are preferably made of flat sheet metal and the intermediate portion through which extends the pivot pin 13 is nearly as wide as the outside diameter of the cartridge head 7. The two intermediate portions 21 of the latches 15 lying side by side extend into and loosely fit within the slots 12-12, but they do not extend radially quite through the said slots 12-12, as clearly shown in Fig. 1.

Within the head 7 and smoothly fitting the cylindrical axially depressed holes or bores 9 and 11 is a push button 22 capable of slight longitudinal movement therein, the smaller rearwardly extending end terminating substantially flush with the outer rear surface of the flange 8. This push button 22 simulates in appearance the percussion cap in the end of a cartridge for real fire arms. The push button 22 is provided with a smooth conical axially disposed recess 23, the walls of which converge rearwardly toward the smaller end of said button. The largest diameter of said recess 23 is at the forward end of the button, but said diameter is preferably not quite so great as the diameter of the bore 9 of the head to provide, when desired, a flat seat 24 for a light coil spring 25, such as is shown in Fig. 4, and which may be compressed between said seat 24 and the rear edges 26-26 of said wide intermediate portions 21 of the latches 15. When a spring 25 is used it may be a light one, its outside diameter is such as to fit smoothly within the bore 9 of the head 7, and its inner diameter should be out of contact with the curved surface 20 of the latches 15. When the cartridge is provided with two latches 15, as above described, and as shown in Fig. 1, the spring 25 may be omitted.

65 Also fitted within the cylinder or casing 1

is a hollow plunger or hammer 27, which is generally cylindrical in shape to slide freely within the cylindrical bore of the tube or casing 1, but it is preferably provided on its forward end with a dome-like projection 28 around which is a narrow circular squared shoulder 29, and at the center of which is an axial hole 30 through the front wall thereof communicating with the chamber 31 within the plunger 27. The rear wall 32 is disposed at right angles to the axis of the plunger 27 and casing 1, and is also provided with an axially disposed hole 33 of a size to permit of the passage therethrough of the pointed ends 18 and the teeth or detents 17 of the latches 15. The hole 30, the chamber 31 and the hole 33 together afford an opening or passage through the projectile and through which air may freely pass.

Normally held pressed against the forward slotted edge or end of the cartridge head 7 is a flat ring or washer 34 forming a seat for the rear end of the stiff coiled propulsion spring 35, which is at all times under a compressive tension between said cartridge head 7 and the rear wall 32 of the plunger or hammer 27. The rear wall 32 is preferably of even thickness to provide a sharp corner 33' over which the teeth or detents 17 may take, to retain the plunger or hammer 27 to the retracted position shown in Figs. 1, 4 and 7.

In assembling the cartridge the plunger or hammer 27 is inserted into the rear end of the cylinder, tube or casing 1, the stiff propulsion spring 35 is next inserted into the casing 1. The cartridge head assembly is made by first inserting into the head from the forward end thereof the push button 22, then inserting the spring 25, when a spring is to be used, then inserting the latches 15-15 with their teeth or detents 17 and their rearwardly extending arms 19 oppositely disposed, as shown in Fig. 1, the wide intermediate portions 21 lying flat against each other loosely fitting into the slots 12-12; then the pivot pin 13 is inserted into the transverse hole 13' through the walls of the head 7 and through the pivotal openings or holes 13' through the latches 15. The ring or washer 34 is then placed over the forwardly projecting arms 16 of the latches 15 and brought to bear on the forward end of the head 7. When so assembled the head 7 is inserted into the rear open end of the tube or casing 1 and held there against the tension of the propulsion spring 35 until the head 7 is rigidly secured to the cylinder or casing 1 by forcing, by a pressing, or by an appropriate spinning operation, the metal of the tube or casing 1 down into the groove 14 of the head 7, thereby forming the groove 6 on the outside of the tube or casing 1.

It should now be made plain that when, after assembly, the plunger 27 is pushed rearwardly, by a short ramrod or other suitable tool inserted through the open tip of the car-

tridge, to the position shown in Figures 1 and 4, the pointed ends or tips 18 will pass through the hole 33 in the rear wall 32 of the plunger 27 and the teeth or indents 7 will catch on the inner face of the wall 32. This action is insured by making the edges 37-37 of the wide portion 21 of the latches 15 flush with the forward end of the cartridge head 7, when that portion of the forwardly extending arms 16 immediately in the rear of the teeth or detents 17 bear against the inner surface of the hole 33 in the rear wall 32 of the plunger or hammer 27 with the detents 17 contacting with the inner surface of the wall 32, and by making the edges 38-38 on the opposite side of the pivot pin 13 to just clear the rear face of the washer 34 when said forwardly extending arms 16 are in said position. When edges 37 and 38 of the latches 15 are so constructed the tension of the propulsion spring 35 will hold the forwardly extending arms 16 yieldingly and in position so that the pointed ends or tips 18 of the latches 15 will enter the hole 33 when the plunger is forced rearwardly and slightly turn the latches 15 on their pivot pin 13 by reason of the engagement of the curved surface, between the detents 17 and the pointed end of the tips 18, with the wall of the hole 33 until the detents 30 shall pass over the edge or corner 33', whereupon said propulsion spring will snap the detents 17 over the shoulder formed by said edge or corner and hold said detents there until they are released therefrom, as will be described below. When the parts are so assembled and arranged the rounded ends or curved surfaces 20 of the rearwardly extending or releasing arms 19 lie close to or in contact with the walls of the bore 9 in the head 7 and preferably against the forward or marginal surface of the conical hole or recess 23 of the push button 22. In each latch 15 the detents 17 and the rounded end or surface 20 are on opposite sides of the latch 15 and on diametrically opposite sides of the pivot pin 13 so that when the push button 22 is pressed inwardly the tapering surface of the conical hole 23 forces the releasing arms 19 toward the axis of the cartridge casing 1 and moves the latches 15 so that the detents 17 move toward the axis of the cartridge against the tension of the spring 35 pressing on the shoulders or edges 37-37 through the washer ring 34, and when the latches are so turned sufficiently to cause the teeth or detents 17 to clear the corner or edge 33' of the hole 33 the plunger 27 will be released and will be impelled forwardly at a high speed by the stiff propulsion spring 35 until the shoulder 29 of the plunger or hammer 27 engages the shoulder 3 at the forward or discharge end of the cartridge, where the forward movement of the plunger will cease by reason of the engagement thereof with the shoulder 3. The forward position

of the plunger 27 is indicated in dotted lines in Fig. 1.

But before the engagement of said plunger with the shoulder 3 the domelike projection 28 of the plunger will strike against the wooden spherical projectile or ball 5 placed in the tapered end of the tip 4 and the impact will project the ball at a high speed out of the shell.

From the above it is believed that it will be plain that to load the cartridge the plunger 27 is first forced forwardly within the shell or casing until the teeth or detents 17 catch over the corner 33' of the hole 33 in rear wall of the plunger or hammer 27, whereupon the plunger will be retained in retracted position against the tension of the compressed propulsion spring 35. A light wooden projectile 5, preferably spherical, is then pressed into the open end of the tip 4 of the cartridge where it remains frictionally held so tightly that it is difficult to remove it except by discharging it therefrom by the impact of the plunger against it. The parts are so proportioned and arranged that when the ball is so inserted into the tip it will project into the path of the movement of the plunger or hammer 27 and be struck by the plunger just before the plunger engages the shoulder 3 of the cylinder or casing.

The ball or projectile 5 is not propelled, impelled, or expelled from the shell or casing 1 by air compressed between the forward end of the plunger 27 and the projectile 5, but by the impact of the plunger against the projectile, for the passage through the plunger 27 provided by the holes 30 and 33 and chamber 31 places the air contained within the cartridge and on opposite sides of the plunger in free communication so that the air circulates within the casing or cylinder from in advance of the plunger to the rear of the plunger as the plunger is impelled forwardly by the spring and very little, if any, pressure is built up in the space between the plunger and the ball or projector.

As soon as the pressure against the button 22 is relieved the button moves rearwardly to the position shown in Figs. 1 and 4. When I use two latches 15, as above described and as shown in Fig. 1, the pressure of the propulsion spring against the shoulders 37 is sufficient to turn them until the edges 37 lie in the plane of the front edge of the cylinder head 7. In so moving the short releasing arms move outwardly away from the axis of the shell and their curved outer surfaces 20, pressing against the conical surfaces of the hole or recess 23 of the push button 22 and on diametrically opposite sides of the push button, cause the push button 22 to slide rearwardly to the position shown in Figs. 1 and 4 without the interposition of any spring between the push button and the forward

edges of the intermediate portions 21 of the latches 15.

In a modified form of my invention shown in Fig. 4 I employ but one latch 15, which in construction is like the latches 15, shown in Fig. 1, and it is mounted in the cartridge head 7 in exactly the same manner as the two latches were in the previously described arrangement, but the slots 12'-12' in the head 7 is only slightly wider than the thickness of one latch 15. In this construction the pressure between the curved surface 20 of the rearwardly extending arm 19 is all on one side of the button 22 and may tend to cause the button to bind in the bores 9 and 11 and not move to its rearmost position by reason of this unbalanced pressure against the conical surface in the rear thereof, unless the parts are very carefully made and fitted and possibly lubricated. To insure an operation wherein the press button will be surely returned to its rearmost position as soon as any pressure thereon from the rear has been released, I preferably mount the spring 25 between the seat 24 and the edges 26-26 of the latch, as referred to above.

It is also to be noted that in assembling the shell, as above described, the only machine work required to be done is the forming of a groove 6 in the wall of the cylinder or tube 1. The pin 13 is merely slipped into the holes 13' of the head but when the shell is assembled the pin cannot be separated or removed, for it is retained in position by reason of the substantial engagement of the ends thereof with the inner wall of the cylinder tube or casing 1.

The modified constructions shown in Figs. 7 to 9 inclusive, are very similar to that shown in Fig. 1 except that the edges of the rearwardly extending arms 19' of the latches 15' are cut away between the curved surfaces 20 and the intermediate portions 21' to provide spaces for the lugs 36, one on one edge only of each latch. Each lug 36 forms a seat for a light coiled spring 39, one end of which surrounds a lug 36 and the other end of which is in an opening 40 through a wall of the head 7. The edge of the neck or reduced portion upon which a lug 36 is provided is slightly further from the axis of the shell or head than is the opposite edge of said reduced portion, so that a spring 40 seated on a lug 36 engages only one latch, and that latch is the one on which the lug is provided. The contact of each spring with one latch only is further insured by drilling the holes 40 at a slight angle to the plane in which the latches oscillate as is clearly shown in Fig. 8. When the springs 39 are inserted in the holes 40, each to surround its respective lug, they may be readily compressed manually or by a suitable implement and so compressed the cartridge head may be slipped into the open end 65 of the shell 1. The springs 39 will thus be

maintained under compression because their outer ends will abut against the inner wall of the shell 1 when the head 7 is in position. These light springs 39 tend to hold the latches 15' in their normal projectile-engaging position, shown in Fig. 7, and to hold the curved surfaces 20 pressed against the tapered recesses 23 in the push button 22. When the push button 22 is pressed inwardly to release the piston or plunger 27 from the latches 15', and the plunger is moved to its forward position under the tension of the propulsion spring 35, and when pressure is thereafter relieved on the push button, the springs 40, acting through the curved surfaces 20 pressing against the button 22, returns the push button to its normal position (its rearmost position, shown in Fig. 7), and the two latches will move to the same position that they are shown in Fig. 7. In this case, therefore, the shoulders 37, which were shown in the modification illustrated in Figs. 1 and 4 as normally in engagement with the washers 34 are, in the present modification, well to the rear of the forward edge of the cartridge head 7 and out of contact with the ring or washer 34 so that the springs 39 operate to hold the latches 15' in plunger-engaging position, and the push button 22 in its rearmost position. In this construction, the function of the spring 35 is merely to impel the plunger 27 forwardly against the projectile 5 when the plunger is released from the latches 15', whereas in the former constructions the tension of the spring 35 also normally maintains the latches 15 in the plunger-engaging position and the push button 22 in its rearmost position.

The cartridge thus provided has the outward appearance of a real cartridge. It may be inserted and withdrawn from the breech of the gun as a cartridge is in a real firearm; the cartridge is all self-contained. There is provided no access to the mechanism inside of the cylinder tube or casing 1, except that the plunger may be forced back to "loaded position" by the insertion of a ramrod through the open tip. The parts are strong, durable and cannot be readily displaced by the operation of the mechanism. A light wooden ball may be propelled at a relatively high speed, but since the mass or weight of the ball is small or light, the impact of the ball is not enough to break a pane of glass or disfigure furniture, nor is any particular discomfort felt if the ball or projectile be fired directly against the hand.

Having thus described my invention what I claim and desire to protect by Letters Patent of the United States is:

1. A cartridge for toy guns comprising a substantially cylindrical shell having one end thereof shaped to frictionally retain a projectile, a plunger in said shell having an opening for the free passage of air therethrough and providing an annular shoulder therein,

- a plunger retaining member in said shell at the end thereof remote from said projectile-holding end, and having a tapering head and a detent for engagement with the edge of said shoulder in said opening to hold said plunger in its inward position within the shell, and a spring for impelling said plunger forwardly into impact with the projectile, when said plunger is released from said member. 5
2. A cartridge for toy shot guns comprising a shell having one end shaped to frictionally retain a projectile, a plunger in said shell provided with an opening for the passage of air therethrough and providing an annular shoulder at the rear end of said plunger, a plunger retaining member secured to that end of said shell remote from said projectile-holding end and having a tapering end and a detent for engagement with said shoulder to hold said plunger in its inward position within said shell, and a spring for forcing said plunger, when released, against said projectile, the said tapering end of said member being normally positioned to slide over said shoulder when said plunger is forced to its rearmost position in said shell. 10
3. A cartridge for toy shot guns comprising a cylindrical shell having one end shaped to frictionally retain a projectile, a plunger slidably mounted in said shell and having an opening therethrough providing an annular shoulder at the rear end of said plunger, a plunger retaining member secured to said shell in the end thereof remote from said projectile-holding end and having a tapering head and a detent for engaging with said shoulder in said opening to hold said plunger in its inward position within said shell, and a spring for projecting said plunger, when released from said member, against said projectile, said opening through said plunger being to permit of the free passage of air from in front of to the rear of said plunger during the forward movement of said plunger. 15
4. In a cartridge for a toy gun the combination of a substantially cylindrical shell having a tip with a slightly tapering bore and providing an inwardly directed shoulder near the open end of said shell, a cartridge head rigidly fitting into the rear end of said shell, a push button co-axially mounted in said head, a latch pivotally mounted within said shell and having an arm extending rearwardly from the pivot of said latch into substantial contact with the said button and an arm extending forwardly from said pivot and provided with a detent, a hollow plunger mounted in said shell and having an air passage therethrough from the front to the rear thereof, and a compression spring mounted in said shell to impel said plunger forwardly against said shoulder at the discharge end 20
- of said shell and slightly into said tip when said plunger is released from said latch. 5
5. In a cartridge for a toy gun the combination of a substantially cylindrical shell having a discharge tip of tapering bore to frictionally retain a projectile, a head mounted in the rear end of said shell and having a circumferential groove in its outer periphery, the material of said shell being forced into said groove to permanently retain said head in said shell and a plunger mounted in said shell to reciprocate longitudinally therein, a latch pivotally mounted in said head to engage said plunger when forced into said shell and a spring to propel said plunger forwardly against a projectile in the end of said shell when said plunger is released from said latch, said shell being provided with a shoulder near the discharge end thereof to retain said plunger within said shell. 25
6. In a cartridge for a toy gun the combination of a substantially cylindrical shell with a discharge tip of tapering bore to frictionally retain a projectile, a cartridge head mounted in the rear end of said shell and fixedly secured thereto, a plunger mounted in said shell to reciprocate longitudinally thereof, and having a free passage for air therethrough, a latch pivotally mounted in said head to retain said plunger within said shell, a spring under tension tending to force the said plunger forwardly to strike a sharp blow against the projectile when said plunger is released from said latch, and a push button in said head and movable forwardly to release said latch from said plunger. 30
7. In a cartridge the combination of a shell having a shoulder near the forward end thereof, a plunger arranged to slide in said shell, a cartridge head rigidly mounted at the rear of said shell and a compression spring normally holding said plunger against said shoulder, a latch having a forwardly extending arm to engage and retain said plunger when said plunger is forced inwardly against the tension of said spring, and having a rearwardly extending arm, a push button mounted in said head and having a tapering surface in substantial contact with said rearwardly extending arm. 35
8. In a cartridge the combination of a shell, a plunger reciprocable therein, a cartridge head rigidly mounted in the rear end of said shell, a compression spring normally tending to force said plunger forwardly, two latches pivotally mounted in the rear end of said shell on a common pivot and each having an arm extending forwardly and provided with a notch or detent, said detents being disposed on opposite sides of the axis of said shell, each latch also having a rearwardly extending arm, said arms being oppositely disposed and extending outwardly from the axis of said shell, and a push button having a conical recess in the inner face thereof, engaged 40

by said rearwardly extending arms when said push button is pressed inwardly to release said detents.

9. In a cartridge the combination of a cylindrical casing, a plunger mounted to reciprocate in said casing, a latch to hold said plunger, a spring between said plunger and latch to propel said plunger forwardly when released from said latch and to hold said latch yieldingly in a position to engage said plunger when forced into said shell against the tension of said spring.

10. In a cartridge for toy guns, the combination of a cylindrical shell, a cartridge head rigidly mounted in the rear end of said shell, a pivot pin mounted in said head, a latch mounted on said pin and having a forwardly extending arm with a detent near the end thereof and a rearwardly extending arm, the end of which is within said head, a plunger mounted to slide within said shell, a propulsion spring compressed between said plunger and said head and engaging said latch to normally hold said detent in a position to engage said plunger, and a push button mounted in said head and operative when pushed into said head to move said rearwardly extending arm to swing said detent out of plunger engaging position.

11. In a cartridge for toy guns, the combination of a cylindrical shell, a cartridge head rigidly mounted in the rear end of said shell, a pivot pin mounted in said head, two like latches mounted on said pin, side by side but oppositely disposed, each having a forwardly extending arm with a detent near the end thereof and a rearwardly extending arm, a plunger slidably mounted in the forward end of said shell and having an opening in the rear wall thereof, a propulsion spring compressed between said plunger and said head and engaging said latches to normally hold them in a position to enter said opening and engage said plunger and hold said plunger in retracted position, and a push button passing through said head and longitudinally slidably therein and having a recess in the inner end thereof with tapering walls to engage said inwardly extending arm and turn said latches in opposite directions to move said detents out of engagement with said plunger when said push button is forced inwardly into said head.

12. In a cartridge, the combination with a shell and a reciprocating plunger therein, of a latch to retain said plunger in retracted position, a push button in the head of said shell and engaging said latch, and a spring normally holding said latch in plunger-retaining position and also operative through said latch to hold said push button in its rearmost position in said head.

In witness whereof, I have hereunto set my hand this 29th day of September, 1926.

FREDERICK HENKE.
